[57] **CLAIM**

The ornamental design for an exteriorly mounted support plate for a vehicle rear brake light, as shown and described.

DESCRIPTION

FIG. 1 is a top plan view of an exteriorly mounted support plate for a vehicle rear brake light showing my new design;

FIG. 2 is a side elevational view thereof as seen from line 2—2 in FIG. 1;

FIG. 3 is an opposite side elevational view thereof;
FIG. 4 is a bottom plan view thereof;

FIG. 5 is an end elevational view thereof, the opposite end being identical; and

FIG. 6 is a bottom perspective view thereof on a reduced scale.
